(57) CLAIM

The ornamental design for a toothpaste and toothbrush travel holder, as shown and described.

DESCRIPTION

FIG. 1 is an isometric drawing shown in exploded assembly of my new design for a toothpaste and toothbrush travel holder with the cover detached from the base and wherein the matter shown in dashed line comprises no part of the invention;

FIG. 2 is an isometric drawing of my new design for a toothpaste and toothbrush travel holder with the cover attached to the base

FIG. 3 is a drawing of a top view of FIG. 2;

FIG. 4 is a drawing of a bottom view of FIG. 2;

FIG. 5 is a drawing of a right side view of FIG. 2 and wherein the left side view is identical;

FIG. 6 is a drawing of a bottom view of the cover of FIG. 2;

FIG. 7 is a sectional view, taken along the lines 7—7 and rotated 180 degrees, of FIG. 2;

FIG. 8 is a drawing of a top view of the base of FIG. 2; and, FIG. 9 is sectional view, taken along the lines 9—9, of FIG. 2.

The cover and base members are shown separately in FIGS. 1, and 6—9, for ease of illustration.
